UNITED STATES PATENT OFFICE

GUSTAV RINGELHAN, OF DRESDEN, GERMANY

STAMPING TOOL FOR KEYS

Application filed September 22, 1926, Serial No. 128,325, and in Germany October 2, 1925.

This invention relates in general to stamping tools for striking up portions of flat metal keys so as to form projecting curves on the same. The struck up curve-shaped projections on different keys are situated at different points of the key bits and thereby a great variety of keys is obtained.

The present invention provides a stamping tool for making such keys and is shown in the drawing in which

Fig. 1 is a front view of the top and bottom parts of the stamping tool;

Fig. 2 is a top view of the bottom part of the stamping tool with positioning plate for 15 positioning the key blank,

Fig. 3 is a top view of the bottom part of the stamping tool with positioning plate and the key blank removed,

Fig. 4 is a section through Fig. 1 on a plane 20 extending at right angles to the surface of the drawing,

Fig. 5 is a section through Fig. 1 on a plane extending parallel to the surface of the drawing and

25 Fig. 6 is a plan view and side view of a key, portions of which have been struck up by the stamping tool so as to form projecting curves.

As shown in Fig. 1 the tool comprises an 30 upper part or patrinx 1 and a bottom part or matrix 2. The patrinx 1 and matrix 2 are each formed with a recess with removable front and rear walls, the front walls each being fastened by four screws as shown in 35 Fig. 1. Each said recess or chamber is divided into two halves by a middle dividing plate which extends from the front to the rear wall or plate of the chamber as shown in Fig. 3. The lower part or matrix 2 is 40 formed with flanges 3 by which it can be fastened on the bed of a press or the like, and the upper part or patrinx 1 has a shaft 4 by which it can be fixed in the ram of the press.

Extending from the front to the rear end 45 of each compartment of the recess in the matrix is a screw spindle 5 which is journaled in the front and rear plates or walls of the chamber and which can be turned by handles 6. Each screw spindle 5 engages 50 with the internal thread of a slide 7 that can

be moved longitudinally in its compartment by turning the handle 6. Embedded in the flank of each slide 7 is a bar 8 which joins a slide 7 in the matrix with a similar slide in the upper part or matrix 1. Fixed in the inner flank of each slide 7 is a pin 9. In the periphery of each handle 6 there is a notch 10 that cooperates with a holding pawl 11. Extending beside the inner flanks of the slides 7 are two stamping members in the form of plates 12. These two plates 12 and the middle dividing wall of plates between the two compartments form the cutting or stamping members of the matrix. They are coupled to their respective slides by being 55 slipped onto the pins 9. The said parts 7, 12 etc. in the compartments are fixed therein by means of screws 13. The member for positioning a key blank in the matrix is made in the form of a plate 14 with slots 15 for 60 receiving the connecting members or bars 8 between the slides in the patrinx and matrix. The positioning plate 14 also has a long notch 16 which receives the key blank 23. A middle line drawn lengthwise through the notch 16 lies beside a middle longitudinal line 65 through the chamber in the matrix and the distance between the two lines is equal to the lateral distance between two curves or projections 24 struck up from the blank, Fig. 6. 70

The chamber and the parts therein in the upper part or patrinx 1 are similar to the chamber and corresponding parts in the matrix except that the slides are slipped over smooth guide bars 17 and the connecting 75 bars 8, instead of being fixed in recesses in the outside flanks of the slides 7, are adapted to slide up and down in recesses 18. The stamping members 19, Fig. 5, in the patrinx have projections 20. The middle plate and 80 other adjacent plates in the patrinx have recesses 21.

When the tool is fixed in position in the press the connecting bars 8 protrude into the channels 18. The stroke of the press is such 85 that the bars 8 never leave the channels 18. Stamping plates 20 are maintained above the bottom stamping plates or matrix cutting plates 12. When the bottom slides 7 with 90 their associated plates 12 are shifted the bars 100

8 cause the slides in the top part or patrinx 1 and their associated stamping plates to execute corresponding movements. A complete travel of the slides is subdivided into ten sections numbered 0 to 9. One such section 5 corresponds to one turn of a handle 6 from the position in which its notch 10 is engaged by its holding pawl 11 to the next position in which the pawl drops into the notch. In the 10 foremost or zero position of the slide the numeral 0 on a number disk 22 belonging to the slide will be in its topmost position as shown in Fig. 3.

When the slides have been set to the desired 15 number on the number disks 22 the screws 13 are made fast and the key blank 23 is then slipped into the notch 16 whereupon the top part or patrinx 1 is forced downwards. The stamping members 20 of the patrinx strike 20 curve-shaped projections 24 out of the flat metal of the blank and force them into the cutting members 12 in the matrix. Such projections 24 can be struck up from both sides of the key blank. To do this the blank is 25 turned over and the projections that have already been struck up from it are then lodged in the recesses 21 in the patrinx. If the tool has four stamping plates 12, 19 and a middle plate as shown, five struck up projections or 30 lines of projections 24 lying beside one another will be produced. The number of projections lying beside one another can be changed at will.

It is necessary to have the middle line of the 35 long notch 16 out of the middle of the chamber in the matrix because when the key blank is turned over for the purpose of striking up projections from its second side, different lines from those already struck up by the projections 20 have to be presented to, or placed 40 beneath, said stamping members 20.

Further differences in the keys produced can be obtained by using different lengths or breadths of the struck up curves or by changing 45 the spacing between adjacent lines of curves.

I claim:

1. A tool for making keys of the kind described comprising a matrix; a patrinx; means 50 for positioning a key blank in the tool; stamping members consisting of longitudinally movable recessed strips in the matrix, longitudinally movable strips in the patrinx, and projections on the latter strips that correspond 55 to recesses in the strips in the matrix; and a connecting member between the strips in the matrix and in the patrinx for causing movements of a strip in the matrix to be accompanied by corresponding movements of a 60 strip in the patrinx.

2. A tool for making keys of the kind described comprising a matrix; a patrinx; means 65 for positioning a key blank in the tool; stamping members consisting of longitudinally movable recessed strips in the matrix, longi-

tudinally movable strips in the patrinx, and projections on the latter strips that correspond to the recesses in the strips in the matrix; a connecting member between the strips in the matrix and in the patrinx for causing movements of a strip in the matrix to be accompanied by corresponding movements of a strip in the patrinx, and recessed spacing members between the longitudinally movable strips in the patrinx and matrix, the recesses in the spacing members being adapted to receive portions of the key blank that have been struck up by said stamping members.

3. A tool for making keys of the kind described comprising a matrix, a patrinx, a plate with a slot for receiving and positioning the key blank in the matrix, adjustable stamping members in the matrix and patrinx whose positions with respect to the slot in said plate can be changed, whereby material can be struck up out of any desired part of the key blank, the middle line extending through said slot, in the direction in which the key blank is slipped into it, being out of coincidence with the middle line or axis of the matrix, whereby 85 a reversal of the key blank in said slot results in different parts of the key blank being struck up by the stamping members, substantially as described.

In testimony whereof I have affixed my signature.

GUSTAV RINGELHAN.
